MULTIPLE PURPOSE GAS UNIT

John L. Bloomheart, Toledo, Ohio, assignor to
Martha F. McKesson

Application March 20, 1944, Serial No. 527,249

4 Claims. (Cl. 128—188)

1

This invention relates to predetermining the selection of a gas or gases in a respective ratio or quantity, with range for maintaining or varying the control thereof, more particularly in the administration uses for analgesia and anaesthesia, as well as for resuscitation.

This invention has utility when incorporated to respond to varying inhalation demands, with possible definite modulation therebetween. The disclosed equipment therefor conducts the gas or gases prescribed to respond to volume measurement, with rate indication. Efficient and economical handling may be readily adopted, involving treatment of exhalation gases and return or re-use of the exhaled gases according to a desired program. The manifold-carrying head with the closely adjacent diverse passage controlling valve body set up a panel-approximating instrument-board-like grouping of the indicating devices with the manually operable valves directly adjacent to forthwith disclose performance.

Referring to the drawings:

Fig. 1 is a general side-elevation of the comprehensive unit embodiment, with parts broken away; the set-up being of a portable apparatus for anaesthesia administration in hospitals or even in emergency at the location where the patient requires service;

Fig. 2 is a plan view of the unit of Fig. 1, partially in section, of the post-carried head and valve body;

Fig. 3 is a somewhat diagrammatic showing of the gas routing or travel thru a flow gage as carried on the head, the diagram of the layout for the flow having top and bottom plans in appropriate register with the intermediate portion, the sequence being illustrated in the three sections at the upper portion of Fig. 2.

Fig. 4 is a view looking down into the absorber-vaporizer control valve body, with the top wall removed, and even to a slight extent in portions therebelow, to show the flow-interrelation valve chambers, not only for fresh gas supply, but of exhalation gas modifying control for absorber handling for carbon dioxide removal, with possible supplemental substance supplied by the vaporizer, such as ether;

Fig. 5 is a fragmentary detail view in vertical section of the absorber valve in the valve body, approximately on the region medially of the ports 76, 64 at the upper right quarter of Fig. 4;

Fig. 6 is also a section from the valve body, approximately in the direction of the line 134 extended upwardly to the left across the port 100, Fig. 4, showing parts of the vaporizer valve; and

2

Fig. 7 is a diagrammatic showing of the valves at the supply region on the manifold, with the flow lines indicated therefrom to the various control valves at the valve chamber body.

Pedestal and gas supplies thereto

Casters 1 support spider arms 2 radiating from a central boss mounting column 3 (Fig. 1). A depending tubular portion 4 mounts a head 5 atop the column or post 3. The head 5 is a primary section or supply manifold carrier for the apparatus.

The major volume gas of supplies whether vitreous oxid or oxygen may be each a compressed gas of tank or cylinder 6 having a head valve 7 adapted to be connected thru a reducing valve 8 to a flexible duct 9 with a connection or fitting 10 to the under side of the after portion of the head 5. With a fitting 10 for each gas supply, these may constitute a row across the back underside of the head 5. In providing for having several gases available, there is rendered readily accessible a wide range for adaptations for use. An instance consistent with the set-up herein disclosed may be for supply of nitrous oxid at the left (Fig. 2) and oxygen at the right. In intermediate these two supplies there may be cyclopropane, ethylene, carbon dioxid and helium.

Direct nitrous oxid and oxygen

The nitrous oxid, from its receiving fitting 10 at the head 5, has a duct 11 to a T or branch fitting 12, with a way 13 on to a manually operable direct flow nitrous oxid control valve 14. This valve 14 as manually opened, say for emergency, or to bring the patient quickly to the desired response, is connected by a duct 15 to a valve body 16, there to be delivered into a chamber 17 (Fig. 4) to pass on therefrom by way of inhalation duct 18 to a fitting 19 (Fig. 1). The Y-fitting 19 has a manually adjustable valve 20. At one position for the valve 20, the inhalation and exhalation of a patient at a mask 21 is thru the valve 20 from and to the atmosphere. At another position of the valve 20, the patient's breathing is not independent of the gas administration unit, but is now connected up to receive gas supply from the duct 18. The exhalation by the patient at the mask 21 may then be by way of the fitting 19 into an exhalation duct 22.

This handling of nitrous oxid is usually to establish the desired stage of analgesia or anaesthesia. For resuscitation, or "bringing back," at the opposite side of the head 5, a manually oper-

able valve 23 may connect an oxygen supply tank for direct oxygen flow by a duct 24 to the body 16. The fresh oxygen gas supply is now in the valve body chamber 17 for ready flow by way of the inhalation duct 18 and the fitting 19 and the mask 21 to the patient requiring attention.

Flow gages

The branch fitting 12 (Fig. 1) for the nitrous oxid supply, as is the case for the oxygen supply, has, as its upwardly extending branch, a duct 25 to a valve housing 26 in which is located a manually adjustable valve 27 at the base of a flow-gage or indicator housing 28. The housing 28 has a front window 29 thru which may be noted rising float positions as to gage markings or graduations along (Fig. 2) a minor scale 30 and a major scale 31. The minor scale 30 may be for smaller readings, as decimal parts of a liter. The major scale 31, even tho of similar overall length, may be hereunder for a plurality of full volume units, as say up to ten liters.

The flow directions of travel in this indicating instrument, one for each of the respective gases, as passing the manually adjustable valve 27, is by a passage 32 (Fig. 3) to the lower portion of an upwardly extending tapering, and in this instance slightly inclined at the top rearwardly, way 33. The broken away portions of the housings 28 (Fig. 2) have placements for the passages diagrammatically set forth (Fig. 3). The indicating means are floats, or light weight objects which may be poised and shifted according to the impetus from the moving gas. A float herein is shown as comprising a base convex portion 34 connected to an upper disk 35 by an intermediate narrowed or neck portion 36.

The taper for the upward way 33 is for a uniform slight enlargement in the cross-sectional area of the passage. Furthermore, with the top or upper portion tilted back or rearwardly, say in the range of 5°, such is sufficient to cause the convex portion 34 of the float to ride along the underside wall and the disk 35 to slide along the upper side wall. The gas flow thrust as inclined upwardly is opposed by the vertical gravity force component in the resultant balance. The experience is that, notwithstanding the gradual enlargement of the crescent clearance about the disk 35 as it ascends, and the converse crescent enlargement as to the lower portion 34, there is minimized, if not total absence of, flutter action for the top-shaped float.

The disclosure is of a construction for accuracy in gage measurements for a low flow rate, while there is available a higher flow rate. The larger flow rate indicator 34, 35, 36 is in the passage 33.

The upper end of the passage 33 has a cross-over 36' therefrom to a down duct 37, a bottom cross-over 38, thence to a riser upwardly tapering way 39 parallel to but of less diameter than the way 33. The taper proportioning for the graduations 30, in tenths of a liter, are for a float 40 in the way 39; and the graduations 31 along the way 33, in liters, for the float 35, 36, 34. The float 40 is of a general similar contour to the float 34, 36, 35, and may be more buoyant as well as of less diameter. As the float 40 is lifted, say to full liter height and so poised, it does not close notched exit from way 39. This gas flow to operate the float 40 is at just slightly lifting or poised of the float 35, 36, 34, near the lower end of the way 33. The further gas flow increase, after the float 40 has fully ascended, now causes the float 35, 36, 34, to rise along the scale 31.

The gas from the passage 39 has a top cross-over way 41 to a down flow way 42, to a bottom cross-over 43, thence to a midback short riser 44, thru a float gage housing mounting flow-off passage 45 to a manifold 46 (Fig. 1) having a hollow post 47 to mount it upon the head 5 for a flow connection with a way 48 in the housing 5. The way 48, as under the upper forward edges of the head 5, extends to a delivery fitting 49 having mounting connection for the valve body 16, and is there in communication with the chamber 17.

Mixed gas flow cut-off

On the body 16 is a manually operable cut-off valve 50 (Figs. 1, 2, 4) having an open or "on" position 51, and, at half turn in the selected direction therefrom, a closed or "off" position 52. The valve member 50 extends into the chamber 17 of the body 16 and there has fixed therewith an eccentric 53 adapted to pull a valve disk 54 against the resistance of a compression spring 55, for thereby positioning the valve disk 54 away from a seat 56. The valve, as thus normally open, allows gas flow 57 from the head 5 into the chamber 17 in the body 16.

Exhalation

The gas flow 57, with or independent of nitrous oxid direct flow 15 or oxygen direct flow 24, may be from the chamber 17 by way of the inhalation duct 18 to the mask 21 and from thence by way of the exhalation duct 22 back to the housing 16. The duct 22 to the body 16 has its flow into a chamber 58 (shown at the lower right of Fig. 4), and thence by an under passage or valve chamber way 59 in the lower portion of the body 16 to the underside of a flutter check valve 60, visible thru a window 61 (Fig. 2). The up flow as lifting the check valve 60 is to an upper chamber way 62 (Fig. 4), from which there is flow—laterally and down (shown at the middle right of Fig. 4) thru a passage 63 to the underside of a valve disk 64 (Fig. 5). The valve disk 64 may be more or less open for flow control into a carbon dioxid absorber or fragment-carrying canister 65, say of soda lime.

Absorber

Conservative practice is for carbon dioxid to contribute to some extent in promoting conditions desired to prevail in anaesthesia. In some proportions, carbon dioxid is an excitant for respiration. In other proportions, it may contribute to the desired stage of analgesia or anaesthesia. It thus is within the control of the operator to remove all or only a portion of the carbon dioxid from the exhaled gas.

The absorber usually has at least some slight heat from exothermic reaction in removing the carbon dioxid from the gas exhaled by the patient. Additionally there may be some moisture. Should the moisture carry thru, gas outflow from the canister 65 by way of its perforate bottom 66 may at once expand into rebreathing bag 67, as a condensing chamber for a more complete removal of moisture, due to the extended outer surface. However, a compact assembly is for the bag 67 to envelop the canister 65. Inasmuch as the bag is readily removable, there is convenient access for canister replacement as such degenerates from a period of use. A minimizing of condensation or moisture in the equipment is an important factor for retaining accuracy in valve performance and the resultant gas supplies.

The positioning of the valve disk 64 away from a lower valve seat 68 is to open the absorber, and

5

toward a valve seat 69 is to check flow of gas exhalation from bypassing the absorber. This manual adjustment is effected thru a knob or head 70 (Figs. 2, 5).

With the knob 70 in register with a position 71, such may be for full "on" for the absorber, that is, for the full volume of the exhalation from the mask 21, duct 22, to the body 16, chamber 58, up thru the flutter valve 60 as shown thru the window 61, thence to pass into the chamber 62, down to the chamber 63, and as the valve 64 is now in its fully lifted position (Fig. 5), the seat 69 is fully closed and the seat 68 therebelow is fully open. The total exhalation flow is accordingly down into the canister 65 for the CO₂ to be removed from the exhalation by the soda lime charge therein. The CO₂ extraction has the residual gas therefrom pass out thru the perforate bottom 66 into the rebreathing bag 67. With clockwise turning, therefrom to a scale 72 for fractional stages to a closed or "off" position 73 (shown in Fig. 2). A still further turning and also clockwise to a position 74 is effective thru a lever 75 (Fig. 5) to move a valve disk 76 against the resistance of a compression helical spring 77 to close a seat 78 and thereby shut off or cut out the rebreathing bag 67. At this fully down position, the valve disk 64 is on the seat 68 and the gas flow from the way 63 is bypassing the absorber and going past the seat 69 into a chamber 79.

Vaporizer

A valve disk 80 (Fig. 6) clear of a seat 81, allows gas flow into a wick-carrying perforate cylinder 82 of an ether vaporizer. The cylinder 82 is in a glass jar or container 83 having a mounting ring 84 to connect the jar with the underside of the valve body 16. Along an exposed vertical side of the jar 83 is a scale of graduations 85 (Fig. 1) which may permit direct reading of the quantity of liquid, as ether, in the jar 83 up to a graduation line. Between the cylinder 82 and the jar 83 is a chamber 88 into which the vapor laden gas from the cylinder 82 may pass, and by a passage 89 in the body 16 to an upper chamber 90 (Figs. 4, 6).

A knurled head 91 (Fig. 2) has a position 93 for full "on", with adjacent clockwise scale 94 therefrom for ether proportion reduction to an "off" position 95. With the handle or head 91 at the position 95, a manual valve 97 at a pouring funnel 98, may be opened, for volatilizable medium, as ether, to be supplied to the jar 83, there to be absorbed by the wick in the cylinder 82.

The weight of the respective knobs 70, 91 is carried by compression helical springs 86. Each knob has a depending internally threaded sleeve or nut 87. For the knob 70, the sleeve 87 lifts and lowers externally threaded stem 87'. The knob 91 operates to lift and lower an externally threaded stem 92.

As the disk 80 (Fig. 6) moves clear of closing the seat 81, it shifts toward closing a valve seat 99. The head 91 operates not only the disk 80, but also a disk 100, which has key against turning or fork engaging stem 101. The holding of the valve devices at the knob 70 from rotation with the knob 70 is effected by the lever 75.

With the disk 80 at the seat 81 to close the vaporizer intake flow, the disk 100, is at a seat 102, to cut off the chamber 90 outflow from the ether vaporizer, from a chamber 103, whereby the gas flow from, or as bypassing the absorber, may likewise fully bypass the ether vaporizer to

6

go to the underside of a flutter check valve 104, visible thru a window 105 (Fig. 2).

With the valve 50 closed, whether or not the knurled head pieces or knobs 70, 91, be in position to shut off the absorber and rebreathing bag, and also the vaporizer, there may be exhalation relief by manually opening a valve 106 in the body 16 (Figs. 1, 2).

The extent to which the absorber is used may be recorded, say as to time intervals of fifteen minutes each, at a scale 107, by a handle 108, at the top of the valve body 16 (Fig. 2) at the other side from that for the valve 106.

Bellows

On the head 5 is a handle or knob 109, adapted as freely turned to carry therewith a pointer 110 over a scale 111, say in liters (Figs. 1, 2). Rotation of the knob 109 is effective thru a toothed disk 112 in mesh with a toothed disk 113 at an angle thereto, thereby to wind a cable 114 having a wrap about the hub of the disk 113. One end of the cable 114 is connected to a tension helical spring 115 fixed with the head 5. The other end of the cable 114 has a wrap at an enlargement 116 fixed with a shaft 117 having exterior of the housing or head 5 an upstanding arm 118 extending to bellows back section 119. Opposite thereto is a fixed bellows front section 120 having a duct way 121 therefrom in the housing 5 to the way 48. To counterbalance the bellows, is a spring 121'.

The rebreathing bag 67 may be shut off, in the event such be not a rigid envelop for the absorber, and a definitely disclosed rebreathing checked at the scale 111 for the full rebreathing to take place in the bellows. The knob 109 may be turned to locate the pointer, say at zero, in an adjusted capacity for the bellows. As the variation be plus or minus, the operator may thereby determine gas reduction or replenishment.

For a minor cylinder or gas supply, as for cyclopropane, there may be a ring 122 on the post 3 below the boss or tubular portion 4 (Fig. 1). From this ring 122, an arm 123 may have a clamp 124 to engage a valve head 125 of a cylinder 126, thereby to be sustained from the post 3 of the portable unit. From the cylinder 126 there may thus be controlled gas flow to the arm 123 and therefrom by a duct 127 lined up in approximate parallelism to the ducts 9 for similar fittings 10 to connect at the rear under portion of the head 5.

In the instance of some administration gases, condensation may occur. To promote accuracy in anaesthesia control, advantage arises in precluding such liquid disturbance factors from further travel into the valve regions of the equipment. To this end, the valve housing 26, below the flow gage main housing 28, say for cyclopropane, may have a drip tube 128 protruding from a hollow depending boss 129 at which is detachably mounted a glass receiver or cup 130. As condensation is noted to collect therein, the cup 130 may be removed, emptied and then replaced.

Use

The unit as herein disclosed is one which may be connected up for the desired gas or gases at the head 5. With the valve body 16 mounted on the head 5, and the mask 21 connected by the ducts 18, 22, the assembly is complete for handling a patient. Exhalation-inhalation cycle is disclosed by the flutter valves 60, 104, to be seen

thru the windows 61, 105, in the top of the valve body 16. The cutoff valve 50 may be to clear of the dosage gases, or to leave the way clear for direct oxygen supply thru the valve 23, for a quick come back or resuscitation. In an emergency to anaesthetize the patient, the nitrous oxide direct flow valve 14 could be operated.

The normal operation of the equipment is with the valve 50 open. The operator may set the pointer 110 at upper mid position when the gas administration has started. Whenever the pointer 110 shows change, the dosage gases and their flow rate quantity may be reset thru the valves 21. There may be total bypassing of the vaporizer. For administration gas economy in recirculation, the extent of absorber operation may be adjusted.

There is an important factor available to the operator in the matter of changing of the cycle or swing of the pointer 110 in response to the rebreathing functioning of the bellows. For the full exhalation to come back thru the absorber to the bellows, the gradual decrease in the bellows maximum capacity position as shown by the pointer 110, is a check on the oxygen consumption should the apparatus be manipulated with such end in view. Should the patient be in some stage of analgesia or anaesthesia which it be desired to maintain, the drop in capacity maximum as indicated by the rebreathing bellows, may be a clue to hold the patient against shifting from the condition established and which it be desired to maintain, that the deficiency should be made up by the supply of additional oxygen. In conducting this replenishment, it is in order to avoid introducing such quantity in excess, but to bring the operation up to swinging the pointer 110 just to the mid position. In the event the needle or pointer 110 gets to swinging too far, or to show a capacity in excess, then it is in order to reduce or cut off the oxygen supply, to bring the pointer 110 in its cycle back to the selected limit. Also, the gradual supply of oxygen, even at an increasing rate, may be adopted for changing from anaesthesia to analgesia, or fully back; altho for quick response the valve 23 is available.

The quantity or proportion of the treatment or anaesthetizing gas or gases may be established to the satisfaction of the operator with the bringing of the pointer 110 to the upper mid-position. This turning of the knob 109 is against the frictional resistance of the cable 114 at the hub of the gear 113 and is not to operate the bellows. However, as the knob is released, the operation of the bellows is effective to shift the pointer 110. In the event the absorber be not removing the carbon dioxide, this may be detected by the gradual increase in the capacity disclosed for the rebreathing bellows by the pointer 110. Effort should be made to have such overcome by the absorber. Here as with oxygen consumption, the safeguarding course is by resort to oxygen supply.

The counterbalance spring 121' renders the bellows sensitive to rebreathing operation. Such incoming supply of gas or gases as may be determined at the manifold on the head 5, may pass therefrom to the plural or multiple chamber valve 17, as indicated by an arrow 131 (Fig. 4).

The integral unit or single body 16 has appended thereto a plurality of gas treatment means. The absorber 65, 67, is subtractive, in that it is designed to effect the reduction in the closed circuit of the carbon dioxide in the ex-

haled breath before such be returned for inhalation. The additive treatment means 82, 83, of the vaporizer, to the extent used, may be a further supplemental supply of a relevant substance, as ether.

The control of the apparatus may be set for fully cutting out the absorber. This is accomplished by locating the valve disk 64 (Fig. 5) on the seat 68 and the valve disk 76 on the seat 78. The result is that the direct or bypassing gas flow from the chamber 63 is to the chamber 79, as indicated by an arrow 132 (Fig. 4).

The control may go still further with the treatment means at the body 16. Whether or not the absorber be wholly, partly, or not at all bypassed, a somewhat similar range of control is available at the vaporizer 82, 83. As there may be a total shutting off of the absorber, as to intake and outlet, such steps may be taken at the vaporizer (Fig. 6). With the disk 80 on the valve seat 81, the inlet port is closed. With the valve disk 100 against the seat 102, outflow from the vaporizer into the stream for inhalation is shut off. That is, the incoming gas flow from the chamber 79 is now to a chamber 133 above the valve disk 80, with the way open therefrom thru the open valve seat 99 for free communication with the chamber 103. This bypassing of the vaporizer is indicated by an arrow 134 (Fig. 4) for the flow to the underside of the check valve disk 104. The rising gas, opening the check valve 104, is now in the chamber 17, to the extent treated or untreated from exhalation, and is now ready to flow from the body 16 by the inhalation duct 18.

What is claimed and it is desired to secure by Letters Patent is:

1. Respiration equipment comprising a head, a manifold unit mounted on the head having a line of parallel intakes thereto, a common discharge therefrom with an intermediate chamber, a panel provided with individually adjustable controls for gas supplies to the respective intakes for the manifold, a variable capacity gas receiver mounted with the head and in open communication at all times with the manifold chamber, an additional flow control body medially forward from the panel in the extent of the panel transversely of the head, said body being in communication with the manifold chamber by way of a passage thru the head, said body including a plurality of valve chambers, an absorber unit, and laterally therefrom, a vaporizer unit, each unit directly and independently upwardly connected to different chambers from the underside of the body to be there supported by the body, relatively movable valves in the body for the absorber and vaporizer units, a mask, and in addition to said relatively movable valves, a manually operable single way valve in the passage from the head to the body for restricting gas flow from the head to the body, and duct means extending from the said flow control body to the mask.

2. Respiration equipment comprising a head, a manifold unit providing a chamber having a tubular discharge post to mount the unit on the head, said manifold having a line of parallel intakes to the chamber, in alignment a panel-like grouping of individually adjustable gas supply flow controls to said intakes, a variable capacity gas receiver mounted back of the intakes adjacent the controls and in open communication at all times with the manifold chamber, an assembly of indicators on the head for the respective controls, each indicator with its control and intake forming an element of the grouping arranged

symmetrically side by side for the extent of the panel unit, a manually adjustable indicator for disclosing receiver fluctuation from a preset indication position therefor, a valve body, there being a passage from the manifold chamber thru the head and providing mounting for the body with the head, exhalation and inhalation passage means to and from the body, and independently relatively movable valve means at the body determining gas flow thru the body and independent of the head.

3. Respiration equipment comprising a head, administration gas supply connections independently thereto, said head having a chamber isolated from said connections, a manifold having a chamber provided with a tubular post mounting connection providing communication between the head and manifold chamber, an adjustable receiver in open communication at all times with the manifold chamber, valve means from the respective supply connections including gage disclosing duct means from the different valve means each into the manifold chamber, gas flow way

means from the head chamber, flow controlling valve means along said way including a housing having partitions therein forming passages in said housing, said partitions being provided with a pair of aligned ports and a third port, a common control valve element reciprocable intermediate the aligned ports, an additional valve element for the third port reciprocable in parallel with the other element, and an inter-connected single control in said housing for moving the elements into and out of port closing positions.

4. For respiration equipment, a controllable gas supply including flow gage means embodying in a gas flow circuit, duct means providing a plurality of successive passage-forming sections in a single connected series, sequential calibration disclosing means in distinctive sets along the respective sections and indicators adapted to have different ranges of location in the duct means in successive response to common gas stream flow through the sections.

JOHN L. BLOOMHEART.
